BOAT CONSTRUCTION

Reinhold Kinte, Brooklyn, N. Y.

Application July 27, 1937, Serial No. 156,020

8 Claims. (Cl. 9—3)

This invention relates to an improved type of boat construction, and more particularly to an improved type of lifeboat or row-boat.

Many casualties attendant upon disasters at sea are ascribed to the type of lifeboat construction heretofore used. For example, many lives have been lost upon the destruction of ships in heavy gale or wind when passengers from the vessel have attempted to board lifeboats after the boats had been discharged from the davits. In the lifeboats of the usual type, a heavy wind causes the boat to dispose itself at right angles to the direction of the wind and of the sea, and accordingly persons in the water trying to climb into the boats often cause the boats to capsize, thereby resulting in at least discomfort and often loss of life of the occupants.

Moreover, in the type of boat construction heretofore employed it has been extremely difficult when using the boat under high winds to dispose it with face directly into the wind because of the tendency, hereinabove referred to, of the boat to turn and dispose itself with its side facing the wind. In an effort to prevent the boat from so disposing itself, sea anchors or drags have been employed, but their use materially increases the amount of energy required to row the boat. In any event, the use of the sea anchor is not a dependable method of maintaining a boat facing into the wind because very often the cord connecting the sea anchor to the boat is broken particularly in a heavy sea because of the great strain placed thereon by intermittent snapping due to the rise and fall of the boat upon the waves.

In the type of boat constructed forming the subject matter of the present invention, means are provided whereby the boat will normally dispose itself facing the wind when freely set adrift without employing a so-called steering oar or sea anchor.

It is another object of the present invention to provide an improved type of lifeboat construction whereby total capsizing of the boat is prevented or at least greatly inhibited so that the boat cannot normally be turned entirely over even though filled with water in a heavy wind and sea.

Another feature of the boat prepared according to the present invention is that it can more easily be rowed into the face of a wind or gale than can boats of the type of construction heretofore used.

It is a further feature of the novel boat according to the present invention that a stream-

line hood is provided at the bow whereby the occupants are at least partially shielded from the elements.

The invention will be fully and comprehensively understood from a consideration of the following detailed description when read in connection with the accompanying drawing which forms part of the application.

In the drawing:

Fig. 1 is a top plan view of an improved life-boat prepared in accordance with the present invention;

Fig. 2 is a side view of the boat illustrated in Fig. 1;

Fig. 3 is a bottom view of the boat illustrated in Fig. 1;

Fig. 4 is a front view of the boat illustrated in Fig. 1; and

Fig. 5 is a sectional view of Fig. 1 taken along the line 5—5.

The improved lifeboat according to the present invention comprises a bow portion, generally designated at 10, a bottom, generally designated at 11, and sides, generally designated at 12. The bottom is substantially of the square-type and generally planar in form with areas cut away along the surfaces, generally designated at 13 and 14, so that the general shape of the bottom is substantially as shown in Fig. 4. The front portion of the bottom is provided with a drag, generally designated at 15, comprising a pair of keels, generally designated at 16 and 17, attached to the bottom strakes of the boat, and having the front ends thereof covered by the shoe, generally designated at 18, so that a covered pocket is provided in the area generally indicated at 19. The other ends of the keels are tapered so that they terminate flush with the surface of the bottom strakes of the boat, substantially as indicated at 20. The sides of the keels are preferably flared outwardly, substantially as shown in Fig. 4. The bow portion of the boat is formed in the shape of a stream-lined hood, generally designated at 21, which presents a substantially circular face and is carried down to the water level. In the preferred embodiment of the present invention, this hood is formed integral with the sides of the boat, generally designated at 11. The air tanks, generally designated at 25, are fixedly attached to and disposed adjacent the sides of the boat, substantially as indicated at Figs. 1 and 2. Seats, generally designated at 26, are preferably provided for occupants of the boat, and disposed adjacent to said seats in the sides of the boat are the oar locks, generally

designated at 27. The stern of the boat is round-tucked to the stern post, generally designated at 30 to which are attached the pintles and gudgeons 31 supporting the rudder 32, substantially as shown in Figs. 1 and 2. In the preferred embodiment of the present invention the rudder 32 is operated by the tiller ropes 33 attached to the tiller handle 34 which is fixedly positioned upon the top of the rudder.

10 The wind rudder, generally designated at 35, is fixedly positioned in the stern of the ship adjacent the stern post and substantially in line with the keel. The wind rudder comprises a hollow air-tight shape substantially narrow at the 15 bottom and substantially widely flared at the top and wider at the top front than at the top back, substantially as shown in Figs. 1, 2, 4, and 5. As has been hereinbefore mentioned, the wind rudder is fixedly attached to the stern post and bottom strakes of the ship so as to be maintained 20 in substantially immovable position. It is preferred that the wind rudder be formed of light metal for example, duraluminum and the like, although other materials can be used, if desired.

25 In use, when the ship is freely drifting in a wind, the keels 16 and 17 act as drags, being the substantial equivalent of sea anchors, and accordingly the boat is turned about the drag, that is to say, substantially about the shoe 18 forming 30 the head of the keels so that the rear of the ship moves as if it were pivoted about this point. This movement is facilitated by the wind resistance provided by the sides of the boat as well as the wind rudder. When the boat is disposed 35 substantially in line with the direction of the wind, it will present a minimum resistance thereto because of the stream-line of the hood 21 and of the wind rudder 35, and accordingly it will remain disposed in this manner relative to the wind, and changes in the direction of the wind 40 will produce corresponding changes in the position of the boat. In the event that persons in the water should attempt to climb into the sides of the boat, thereby causing partial capsizing of same, the air-tight wind rudder 35 in conjunction 45 with the air tanks 25 will prevent total overturn of the boat due to the buoyancy of wind rudder and also due, at least in part, to the torque action exerted by the weight of the keels 16 and 17. The buoyancy of the wind rudder 50 is such as to prevent complete overturn of the vessel.

It is to be understood that this improvement is capable of extended application and is not confined to the exact showing of the drawing 55 nor to the precise construction described and, therefore, such changes and modifications may be made therein as do not affect the spirit of the invention nor exceed the scope thereof as 60 expressed in the appended claims.

What is claimed is:

1. A relatively small boat of the type described such as a lifeboat comprising a hull having a bottom, sides and a hooded bow, a plurality of 65 projecting keel-like elements attached to the bottom of the bow, and hollow, gas-filled and gas-tight element substantially fixedly mounted, in essentially upright position, near the stern portion of the boat projecting above the sides thereof, said element being streamlined whereby the wind resistance presented by the element to wind directed to the side thereof is of a materially greater order of magnitude than the resistance 70 presented to wind directed to the front face thereof.

2. A relatively small boat of the type described such as a lifeboat comprising a hull having a bottom, sides and a hooded bow, a plurality of projecting keel-like elements attached to the bottom of the bow, and an intrinsically buoyant element substantially fixedly mounted, in essentially upright position, near the stern portion of the boat projecting above the sides thereof, said element being streamlined whereby the wind resistance presented by the element to wind directed to the side thereof is of a materially greater order of magnitude than the resistance presented to wind directed to the front face thereof, the element being disposed in the boat so that the condition of minimum wind resistance obtains when, and only when, the boat is disposed substantially parallel to the direction of the wind. 10 15

3. A relatively small boat of the type described such as a lifeboat comprising a hull having a bottom, sides and a hooded bow, a plurality of 20 projecting keel-like elements attached to the bottom of the boat, and an element substantially fixedly mounted, in essentially upright position, near the stern portion of the boat projecting above the sides thereof, said element being streamlined whereby the wind resistance presented by the element to wind directed to the side thereof is of a materially greater order of magnitude than the resistance presented to wind directed to the front face thereof, said element being hollow, gas-filled and gas-tight, whereby 25 its buoyant properties at least largely prevent the boat from completely overturning in the water.

4. A relatively small boat of the type described such as a lifeboat comprising a hull including a 35 bottom, sides and a hooded bow, a plurality of projecting keel-like elements attached to the bottom of the boat, and an element substantially fixedly mounted near the stern portion of the boat projecting above the sides thereof and 40 upright relative to the bottom of the boat, said element being streamlined whereby the wind resistance presented by the element to wind directed to the side thereof is of a materially greater order of magnitude than the resistance presented 45 to wind directed to the front face thereof, the element being disposed in the boat so that the condition of minimum wind resistance obtains when, and only when, the boat is disposed substantially parallel to the direction of the wind, said element being hollow, gas-filled and gas-tight, whereby 50 its buoyant properties at least largely prevent the boat from completely overturning in the water.

5. A relatively small boat of the type described, such as a lifeboat, comprising a hull having a 55 bottom, sides and a hooded bow, the hood of said bow being formed integral with and projecting above the sides of the boat and being substantially streamlined above the water level so that its wind resistance is least when directly facing the wind, a plurality of projecting keel-like elements attached to the bottom of the boat, and a hollow, gas-filled and gas-tight element substantially fixedly mounted, in essentially upright position, near the stern portion of the boat, said element being streamlined, whereby the wind resistance presented by the element to wind directed to the side of the boat is of a materially greater order of magnitude than the resistance 65 presented to wind directed toward the front face of the boat.

6. A relatively small boat of the type described, such as a lifeboat, comprising a hull having a bottom, sides and a hooded bow, a plurality 70 75

of projecting keel-like elements attached to the bottom of the boat and being tapered so that they lie flush with the bottom surface near the mid-portion of the boat, and a hollow, gas-filled 5 and gas-tight element substantially fixedly mounted in essentially upright position near the stern portion of the boat projecting above the sides thereof, said element being streamlined, whereby the wind resistance presented by the ele- 10 ment to wind directed toward the side thereof is of a materially greater order of magnitude than the resistance presented to wind directed toward the front face of the boat.

7. A relatively small boat of the type described, 15 such as a lifeboat, comprising a bottom, sides and center board and having a hooded bow, said hood being formed integral with and projecting above the sides of the boat and being substantially streamlined above the water level so that 20 its wind resistance is least when directly facing the wind, a plurality of projecting keel-like elements attached to the bottom of the bow and disposed substantially parallel to the center board of the boat and being tapered so that they lie 25 flush with the bottom surface near the mid-portion of the boat, a shoe covering the front ends of said keel-like members, and an element sub- 30 stantially fixedly positioned near the stern portion of the boat projecting above the sides there- 35 of and disposed upright relative to the bottom of the boat, said element being streamlined whereby the wind resistance presented by the element to wind directed toward the side thereof is of a materially greater order of magnitude than the resistance presented to wind directed 40 toward the front face thereof, the element being disposed in the boat so that the condition of minimum wind resistance obtains when, and only when, the boat is disposed substantially parallel to the direction of the wind, said element being hollow, gas-filled and gas-tight, whereby its buoyant

properties at least largely prevent the boat from completely overturning in the water.

8. A relatively small boat of the type described, such as a lifeboat, comprising a bottom, sides and center board and having a hooded bow, said hood being formed integral with and projecting above the sides of the boat and being substantially streamlined above the water level so that its wind resistance is least when directly facing the wind, a plurality of projecting keel-like elements attached to the bottom of the bow and disposed substantially parallel to the center board of the boat and being tapered so that they lie flush with the bottom surface near the mid-portion of the boat, a shoe covering the front ends of said keel-like members, and an element sub- 15 stantially fixedly positioned near the stern portion of the boat projecting above the sides there- 20 of and disposed upright relative to the bottom of the boat, said element being streamlined whereby the wind resistance presented by the element to wind directed toward the side thereof is of a materially greater order of magnitude than the resistance presented to wind directed 25 toward the front face thereof, the element being disposed in the boat so that the condition of minimum wind resistance obtains when, and only when, the boat is disposed substantially parallel to the direction of the wind, whereby the boat 30 when freely drifting and disposed with its side facing the direction of the wind will be turned by the torque action exerted by the force of the wind against said element disposed in the stern of the boat, the bow being held in relatively fixed position by the keel-like members which serve 35 substantially as sea anchors, the aforesaid wind resistant element disposed adjacent the stern of the boat being hollow, gas-filled and gas-tight, whereby its buoyant properties at least largely prevent the boat from completely overturning in 40 the water.

REINHOLD KINTE.
